No 877.

Design for a Radiator Stove, by N. S. Yedder.
Assignor to Messrs. Galbraith & Cassell, Jacksonville, Ill.

Patented March 24, 1857.

A. S. Vedder, of Troy, N. Y.
Assoc'to.
Galbraith & Cope, of Jacksonville, Ill.
Letters Patent No. 877, Dated Mar. 24, 1857.

The Schedule referred to in these Letters Patent and making part of the same.

To all whom it may concern:

Be it known that A. S. Vedder, of the City of Troy, in the County of Rensselaer, and State of New York, have invented or produced a new and original Design for a Radiator Stove called the "Economy" and I do hereby declare that the following is a full and exact description of the same, reference being had to the annexed perspective drawing making a part of this specification.

A, is the oval front plate having the oval fire-door B, in its centre. The plate A, has the bead moulding a, on its edge; the swelling moulding b, around the fire door, and ornamented with the leaf-like rosettes c, and scroll leaves d, arranged alternately in a series; and the rising rays e, proceeding from behind the ornament g, on the top of the plate, and bearing the waved streamer f. The oval fire-door B, is ornamented with the border moulding h, studded with the scroll-leaves i, and the panel ornaments, consisting of the expanded rosette j, having its lower half occupied with the ornamented air ports k, and surmounted by the combination of scroll leaves l. The hearth plate C, with its slide C', is ornamented with the braed border moulding m. Each foot D, is scroll form, and is ornamented with the turgid leaf n.

F, is the smooth sheet iron casing, which connects the front plate to the back plate O, the design of which latter plate is like the front-plate and fire-door united.

The illuminating door H, in the

side of the casing is composed of separate pillars *e*, united at the top by the combined scrolls and leaves *f*, and at bottom by the combination of leaf scrolls and mouldings *g*. The oblong frame *h* of this door is ornamented with the ornamented ring *i*, at the corners and middle of the sides, and between these with a series of the compound ornament *j*.

The square pyramidal pivot-hole frame *K*, mounted on top of the casing, is ornamented with the braces *t*, at the sides, and the leaflets *u*, in the corners of the top. The surface of the pivot-hole cover *K*, is of diamond check work,

What I claim as my invention or production and desire to secure by letters patent is.

The ornamental design and configuration of the end plate with its fire door, hearth, and feet; of the illuminated side door with its frame; and of the pivot hole frame with its cover, all as herein described and represented in the annexed drawing.
